UNITED STATES PATENT OFFICE.

RIMMON H. HANSEE, OF MONTICELLO, NEW YORK.

JAR-FASTENER.

SPECIFICATION forming part of Letters Patent No. 639,559, dated December 19, 1899.

Application filed August 25, 1899. Serial No. 728,488. (No model.)

To all whom it may concern:

Be it known that I, RIMMON H. HANSEE, a citizen of the United States, residing at Monticello, in the county of Sullivan and State of New York, have invented a new and useful 5 Jar-Fastener, of which the following is a specification.

This invention relates to jar-fasteners, and has for its object to provide a simple and effective device of this character adapted to 10 exert a forceful pressure on the jar-top when in locked position and capable of being operated by the exercise of a comparatively small amount of exertion and embodying structural 15 features which will reduce the cost of manufacture and afford easy means of application without injury to the jar and which may also be disconnected from one jar and applied to another.

20 The present device embodies the characteristics of an ordinary bail-fastener without the annoyance incident to the irregularity and impositiveness of such devices and also involves in its operation the salient features 25 of a cam-lock without the disadvantage of the variable pressure exerted by such well-known form of jar-fastening owing to the inability to make them fit all sorts of jars and because they are not self-adjustable. The present 30 fastener exerts in its operation a contractive force on diametrically-opposed connecting elements carried by the jar and in a plane at right angles to the plane of applied power. During this operation the present fastener 35 automatically yields while its parts are changing center, and the resultant position of the locking devices is such that it will be impossible for the jar-top to in the least move from its seat or become loose, but adapted when the 40 fastener is entirely released and disconnected to fully clear the mouth of the jar and form no obstruction whatever to the free removal or outpouring of the contents.

The invention consists of the construction 45 and arrangement of the several parts, which will be more fully hereinafter described and claimed.

In the drawings, Figure 1 is a perspective 50 view of a jar-top and a part of a jar, showing the improved fastener applied thereto in locked position. Fig. 2 is an elevation, partially in section, showing the improved fas-

tener applied to the jar and the parts in the position assumed when pressure is first applied to arrange them in locking position. 55 Fig. 3 is a detail perspective view of the locking element of the fastener. Fig. 4 is a similar view of a portion of the resistance and supporting elements.

Similar numerals of reference are employed 60 to indicate corresponding parts in the several views.

The numeral 1, as clearly illustrated in Fig. 2, designates a locking element, and 2 a resistance and supporting element, which is 65 clearly shown in detail by Fig. 4. The locking element 1 comprises outwardly directed or inclined yielding coils 3, having the inner terminals continued into an operating-yoke 4 of considerable length and having its looped 70 extremity 5 made with a pronounced deflection at an angle to the body of the yoke to cause it to assume a close position to the jar-top when the fastener is locked and as shown by Fig. 1. The yoke 4 adjacent the innermost coils of the series of coils 3 is divergent 75 and from this widest point gradually converges to a point adjacent the bend made to produce the deflection of the looped extremity 5. The opposite members of the yoke 4 80 become continuous with the coils 3 at the bases of the latter. The outer terminals of the coils are projected and shaped in the form of contracting arms 6. These arms 6 are inclined upwardly, and the ends are constructed 85 with short bends to provide partial hooks 7. The yoke 4 and arms 6 are on opposing sides of a longitudinal line drawn centrally through the series of coils 3, and the partial hooks 7 have an inward direction. It will be observed that this locking element is formed 90 from a single piece of spring-wire of suitable gage and, as will be more fully hereinafter explained, embodies self-adjustable features. 95

The resistance and supporting elements 100 each comprise a semicircular band 8, having one free end formed into a downwardly-turned hook 9, located under the adjacent part of the said band. The opposite extremity is first formed into a loop 10 to form an eye 11 and then extended vertically or in a plane at right angles to the band to form an arm 12, having the upper end provided with a hook 13. Each of these resistance and sup-

- porting elements are made of spring-wire and are counterparts of each other, and when applied they are reversed, so that the hook 9 of each will be connected to the eye 11 and the 5 arms 12 be disposed at diametrically opposite points on the upper part of the jar-body, and are primarily made long enough to locate the hooks 13 above the upper surface of the jar-top 14, as clearly shown by Fig. 1.
- 10 By reversing the elements 2 in the manner stated the hooks 13 will also have their open portions or entrance-throats in opposed position. The method of applying the resistance and supporting elements in connection with 15 the upper part of the jar-body is very simple and can be quickly accomplished, and it will be seen that there is no particular construction of jar-body necessary to accommodate the said resistance and supporting elements.
- 20 In assembling the elements of the fastener and after the resistance and supporting elements 2 have been applied to the jar-body in the manner set forth the jar-top 14 is placed in position between the arms 12. It is preferred that the jar-top have an upper concaved seat 15, though this is not actually necessary to the practical working of the fastener, but under ordinary conditions gives the best result and will be explained in connection 25 with the operation of the fastener. The partial hooks 7 of the arms 6 of the locking element are then caught in the hooks 13 of the arms 12 of the supporting and resistance elements, as clearly shown by Figs. 1 and 2, and 30 a pull is exerted on the loop extremity 5 of the yoke 4 with a downward tendency. By a continuation of this applied operating force the series of coils 3 disposed on opposite sides of the transverse central line through the locking element will contact with the concaved seat 15 of the top 14 and be first drawn together, as shown by Fig. 2, and slightly pull inwardly on the arms 12 and maintain this position until after the center is passed, when 35 the coils will begin to diverge until they reach their maximum separation, as shown by Fig. 1. During this operation it will be understood that the arms 6 have been turning in the hooks 13; but the downward pressure on the coils 40 and the resistance offered by the arms 12 to a regular overturn of the arms 6 with the series of coils 3 will spring down the said arms 6 and exert a slight torsional twist thereon and produce a strong frictional lock, which 45 will be maintained as long as the series of coils are in diverged positions and in overturned condition when in locked position, as shown by Fig. 1. Owing to the fact that the coils 50 when in locked position have moved past the center and, furthermore, in view of the plurality of frictional contact-points provided by the individual coils accidental disengagement or loosening of the locking element from the position shown by Fig. 1 is completely ob-
- 55 structed and prevented. It will also be observed that when the locking element is turned down to a locking position, as well as in open-
- ing the same, the fulcrum is continually changing, and when the initial locking pressure is exerted on the yoke 4 the arms 6 are not drawn 70 against the surrounding lip of the jar-mouth or any other part of the jar-body with a crushing and unyielding pressure, and though the said arms 12 may be slightly drawn inward they have a yielding movement of themselves 75 and are permitted to at all times substantially preserve their identity as to position by the resiliency of the coils, which will separate or give, as will be readily apparent. Furthermore, the contact of the series of coils is at opposite points on the jar-top and rounded surfaces contact with the jar-top at said points of bearing, and therefore it will be appreciated that sticking as well as fracture will be prevented. In disconnecting the locking ele- 85 ment the partial hooks 7 may be detached from the hooks 13 very quickly and entirely clear the lid or jar-top of any obstruction to its free removal. This will also permit the contents of a jar to be made freely accessible or facilitate the outpouring of the same. 90
- The elements composing the fastener can be made in various sizes, and to suit different applications changes in the form, proportions, and minor details of construction might 95 be resorted to without departing from the spirit or nature of the invention.
- Having thus described the invention, what is claimed as new is—
1. In a jar-fastener, the combination of resistance and supporting members including upward projections with bent terminals reversely arranged at diametrically opposite points, and a locking element comprising opposite arms adapted to be removably connected to said projections and having self-adjustable yielding coils between them. 100
  2. In a jar-fastener, the combination of resistance and supporting elements including upward projections with bent terminals reversely arranged at diametrically opposite points, and a locking element comprising oppositely-extending arms adapted to be removably connected to said projections and having self-adjustable yielding coils between them, connected by an operating pressure-receiving device. 110
  3. In a jar-fastener, the combination of resistance and supporting elements including projections with bent terminals reversely arranged at diametrically opposite points, and a locking element comprising automatically-adjustable rotatable coils having outwardly-extending arms to removably connect with the said projections. 120
  4. In a jar-fastener, the combination of resistance and supporting elements comprising counterpart members reversely arranged and connected to provide diametrically-disposed projections, and a locking element comprising automatically-adjustable rotatable coils having outwardly-extended and normal upwardly-directed arms to removably connect with the said projections. 125

5. In a jar-fastener, the combination of resistance and supporting elements including projections at diametrically opposite points, and a locking element comprising automatically-adjustable rotatable coils having outstanding upwardly-extending arms to removably connect with the said projections and an intermediate yoke, the yoke and arms being on opposite sides of a central longitudinal line through the coils.

6. In a jar-fastener, the combination of resistance and supporting elements comprising counterpart members each having an upwardly-extending projection at one end and a locking element at the opposite end, the said members being reversely arranged to dispose the projections at diametrically opposite points, the latter having terminal bends also in reverse position when the parts are

assembled, and a locking element having members adapted to engage the said projections.

7. In a jar-fastener, the combination of a supporting element composed of two parts having projections with upper hooked terminals, and a locking element comprising coils with outwardly-projecting arms terminating in partial hooks to engage the said hooked terminals and also provided with an intermediate pressure-receiving yoke having an outer deflected extremity.

In testimony that I claim the foregoing as my own I have hereto affixed my signature in the presence of two witnesses.
